UNITED STATES PATENT OFFICE

JOHN J. PUNKE, OF DETROIT, MICHIGAN, ASSIGNOR TO HUPP MOTOR CAR CORPORATION, OF DETROIT, MICHIGAN, A CORPORATION OF VIRGINIA

DESIGN FOR A VEHICLE BUMPER

Application filed August 5, 1929. Serial No. 32,298. Term of patent 3½ years.

To all whom it may concern:

Be it known that I, JOHN J. PUNKE, a citizen of the United States of America, residing at Detroit, in the county of Wayne and State of Michigan, have invented a certain new, original, and ornamental Design for Vehicle Bumper, of which the following is a specification, reference being had therein to the accompanying drawing, forming a part thereof.

Figure 1 is a front elevational view of a bumper showing my new design.

Figure 2 is a fragmentary top plan view of the bumper shown in Figure 1.

Figure 3 is a fragmentary front elevational view of the bumper shown in Figure 2.

Figure 4 is a sectional view taken on the line 4—4 of Figure 3.

I claim:

The ornamental design for vehicle bumper substantially as shown.

JOHN J. PUNKE.
